TEMPERATURE INDICATING DEVICE FOR
WASHING MACHINES

David A. Lundy, Riverside, Ill., assignor to Electric Household Utilities Corporation, Chicago, Ill., a corporation of Illinois

Application February 17, 1937, Serial No. 126,173

9 Claims. (Cl. 73—343)

This invention relates to temperature indicating devices, and more particularly to devices of the type that are especially adapted for use in connection with liquids such as in washing machines and the like.

In the clothes washing art it is well known as a result of experiment and scientific tests that the temperature of the water or washing fluid during the process of washing clothes, as well as the particular characteristics of the fabrics of the clothes being washed, constitute two very critical factors that must be considered when it is desired to obtain efficient and uniform cleansing of the clothes. For example, it has been found that for certain fabric materials such as wool, cotton, silk, etc., the temperature of the washing fluid used in connection with such fabrics desirably should fall within a certain range to insure efficient washing of the clothes. In some instances, if the temperature of the washing fluid is too low the fabrics do not become cleansed efficiently during a normal period of operation of the washing machine. While, on the other hand, if the temperature of the washing fluid is too high there is a tendency to cause the dirt to more firmly adhere to the fabric, and stains, such as caused by perspiration, to become set.

Materials of certain types, such as rayon, should not be washed in hot water as it tends to soften the material and causes disintegration, while with other fabrics, such as wool, excessive shrinking results. It is well known that soaps do not readily dissolve in the washing fluid that is cool, hence it is highly desirable to use water or washing fluid at the highest temperature possible, as may be determined to be proper by the characteristics of the material being washed. Furthermore, certain fabrics which contain dyes or other coloring matter must also be washed in fluids of a certain temperature range in order to avoid running or fading of the dyes or other coloring matter.

In a vast number of washing machines now being used in the homes and apartment dwellings the washing operation is performed in a hit-or-miss fashion as far as the temperature of the washing fluid is concerned. This not only results in inefficient washing of the fabrics but in frequent instances necessitates operation of the machine for longer periods of time than are necessary, resulting in materially reducing the life and serviceability of the fabrics, as well as imposing excessive and unnecessary wear and tear on the machine.

The present invention contemplates the provision of a temperature indicating device in associa-

tion with a movable impeller or agitating member of the washing machine in a manner for conveniently indicating the temperatures of the washing fluid, to assist in efficiently washing fabrics and clothes of various characteristics.

One of the objects of this invention resides in the provision of a novel construction wherein a temperature indicating element is fixedly associated with a part of the impeller of the washing machine and disposed in a position to be conveniently observed when the tube of the machine is filled with washing fluid to its normal operating level.

Another object is to provide a novel construction and mounting of a temperature indicating device in association with a washing machine impeller member which is formed of metal of high heat conductivity.

A further object is to provide a novel construction wherein a temperature indicating device is formed as a permanent part of the impeller of a washing machine and which is simple in construction, efficient in operation and capable of being economically manufactured.

Another object is to provide an improved device of the character indicated which may be quickly attached or detached from the impeller member of a washing machine for purposes of repair or replacement.

Other objects and advantages of the present invention will be apparent in the following description, taken in connection with the accompanying drawings in which:

Fig. 1 is a fragmentary view, part in elevation and part in section, of a washing machine tub having an impeller member mounted therein, provided with a temperature indicating device constituting the present invention.

Fig. 2 is a transverse vertical section through the top of the impeller member and the temperature indicating device.

Fig. 3 is a top plan view of the indicating device.

Fig. 4 is a transverse section through the temperature indicating device taken as indicated at line 4—4 on Fig. 2.

Fig. 5 is a transverse vertical section through the upper end of an impeller member and a modified form of temperature indicating device.

Fig. 6 is a plan view of the modified form of indicating device.

Fig. 7 is a view in side elevation of the modified form of device shown in Fig. 5, with a portion of the housing broken away to show the internal construction of the indicating device.

Fig. 8 is a transverse vertical section through the upper end of the impeller member and a further modified form of temperature indicating device.

5 Fig. 9 is a plan view of the temperature indicating device shown in Fig. 8.

In its broadest aspect the present invention is directed to the provision of a temperature indicating device in association with a movable impeller or agitator member in a washing machine, wherein said impeller member is formed of metal of high heat conductivity, such as aluminum. For purposes of illustration I have shown in the drawings a conventional form of tub 10 of a 10 washing machine in which a movable impeller or agitator member 11 is mounted centrally therein, above the bottom and in spaced relation to the side wall to permit circulation of the clothes and fluid around and beneath the impeller. In 15 the construction shown in Fig. 1 it may be understood that the impeller member which is normally disposed at an angle oblique to horizontal, is bodily rotatable in an orbit about a vertical axis of the tub, and may be operated by driving 20 mechanism of the type similar to that disclosed in the co-pending application of John Whyte, Serial No. 121,922, filed January 23, 1937. It 25 will be manifest, however, that the present invention is equally applicable to impeller members 30 of various types, such as those rotatable about their own vertical axis.

The upper end of the impeller member 11 is formed with an up-standing projection 12, the external lateral surface of which is formed with 35 an annular groove 14. Mounted on said projection 12 is a head 15 containing a temperature indicating mechanism. Said head 15 includes a main body portion 16 adapted to surround the projection 12 and having its lower marginal edge abutted against an annular flange or ring 17 for 40 maintaining it seated against a transverse upwardly facing shoulder 11a of the impeller member, surrounding the projection 12. Said body is provided with a set screw 18 extending into 45 the annular groove 14 of the projection of the impeller member for firmly locking said head in place thereon, and simultaneously securing the element 17 in position. The element 17 is of such size and shape as to constitute a convenient hand 50 grasp for removing the impeller member from the impeller shaft which is designated at 19.

The upper surface of said body 16 is formed with an upwardly open cavity or recess 21 in which is disposed a horizontally extending bimetallic strip 22 of spiral formation, having its 55 outer end anchored as seen in Fig. 2, to a depending leg 23 of a bracket 24 which in turn is secured to the under side of a transversely extending dial 25 seated upon the upper surface of an upstanding marginal flange 16a of said body 16. 60 The inner end of the spirally coiled bimetallic strip is connected to a vertically disposed mounting pin 26 journaled in the bracket 24, and said dial 25. The upper end of said pin projects above 65 the upper surface of the dial and has rigidly secured thereto an indicating element 28 extending parallel to and above the upper surface of the dial 25 for registration with a graduated scale 25a of said dial.

70 Said dial and indicating element 28 are enclosed and protected by a transparent cover 30, the marginal edges of which are embraced at opposite sides by annular gaskets 31. The cover, together with the dial, are assembled in fixed 75 relation to the body 16 by means of a cap 32

having a tubular skirt 32a threadedly engaged with the outer surface of the body 16 while its upper end is formed with an in-turned annular flange 33 adapted to overlie the gaskets and the marginal edge of the cover 30 for tightly clamping said marginal edge and gaskets against the upper surface of the flange 16a of the body 16 and thereby forming a fluid-tight seal for precluding the passage of fluid beneath the cover element 30. It is to be understood that the cover element may be formed of glass but desirably is formed of material such as pyroxylin, so that said cover element may not be easily broken. It will now be apparent that by reason of the fact that the impeller member 11 is formed of metal of 15 high heat conductivity and due to the substantial surface engagement of the body 16 with said impeller member, the bimetallic strip 22 will respond quite readily to the temperature changes of the impeller member 11, the temperature of 20 which will be substantially the temperature of 25 the washing fluid within the tub.

It is to be understood that the graduated area 25a of the dial 25 need not necessarily be formed for indicating temperature in degrees, but may 25 be graduated in a manner to indicate suitable temperature ranges for the washing of garments or fabrics of certain definite characteristics. It is also to be understood that the head 15 associated with the upper end of the impeller member desirably is constructed and designed so that the temperature indicating dial 25 will always be disposed above the normal operating level of the washing fluid in the tub. It will be apparent that the temperature indicating device, when associated with the impeller, is located in a most efficient zone to permit measuring the average temperature of the entire body of washing fluid. Moreover, the vibration of the impeller member when in operation serves to destroy static friction 30 that may set up in the bimetallic strip.

The modified form of my invention disclosed in Figs. 5 to 7 comprises a body 35 connected to the upper end of the impeller member 11b in the same manner as above described in connection with the construction shown in Figs. 1 to 4. Said body is formed with a pair of transversely spaced apart upwardly extending ears or standards 36, the upper ends of which are slotted as indicated at 36a, to provide a seat for a horizontally extending pin 37 which is rigidly secured in place by crimping the metal at the upper ends of said slots, inwardly as seen in Fig. 5. A vertically disposed spirally coiled bimetallic element 38, is positioned between said up-standing ears 36 as seen in Fig. 7 with the inner end of the coil rigidly connected to said pin 37. The upper surface of the outer convolution of the bimetallic strip is graduated as indicated at 39 for registration with an apertured window formed in the rounded top of a housing 40 which encloses said bimetallic strip. Said housing is of thimble-like form having its lower marginal portion rigidly secured on a reduced neck 35a at the upper end of said body portion 35 forming a fluid-tight seal. The upper end of said body is formed with an opening 41 beneath which a transparent panel 42 is mounted in sealing engagement around the marginal edges of said opening by a frame 43 which is rigidly secured to the inner surface of 70 said housing 40 such as by spot-welding. Desirably the outer marginal edges of said transparent panel are embraced by gaskets 44 to form a fluid-tight seal to preclude the passage of fluid through said opening 41, to the interior of the 75

housing 40. A pair of opposite edges of said opening are formed with inwardly extending indicators 41^a for registering with the graduations on the upper surface of the outer convolution of the bimetallic strip 38. A roller 45, carried in a bracket 46, is secured to the inside of the top of housing 40 in position for contact with the outer convolution of the bimetallic element 36, for guiding and confining said element during its 10 expanding and contracting movement.

By reason of the metal-to-metal contact of the impeller 11^b with the body 35 and the up-standing ears 36 of said body with the bimetallic element 38, said bimetallic strip will respond rather 15 quickly to the temperature changes of the impeller member 11^b which, as above mentioned, will correspond approximately to the temperature of the washing fluid.

A further modification of my invention is 20 represented in Figs. 8 and 9, wherein the head connected to the upper end of the impeller member 11^c includes a body 50 secured to said impeller in a manner as above described in connection with Figs. 1 to 4. Said body is provided with 25 an upwardly-open cavity or recess 51 of substantial depth having one or more laterally opening ducts or apertures 52. Disposed in said recess is a bulb portion 54 of a fluid-type thermometer element 55, the tube portion 56 of which projects 30 above the upper surface of the body 50, and is of arcuate formation as seen in Fig. 9. The upper surface of said body 50, over which the arcuate portion 56 of the thermometer is disposed, extends in an upwardly inclined direction 35 as seen in Fig. 8, and said arcuate portion of the thermometer is correspondingly inclined so as to insure efficient responsive action of the fluid in the thermometer and thereby preclude separation of the fluid due to vibration, which 40 might take place if said arcuate portion extended in a true horizontal direction. Said arcuate portion 56 is secured to the upper surface of said body 50 by a pair of clips 57 while the bulb portion 54 is supported and anchored in the recess 45 51 by a body of cementitious material or cork as indicated at 58.

The outer marginal edge of the upper portion of the body 50 is formed with an up-standing annular flange 50^a on which is seated a transparent cover element 60, the outer marginal edges of which are embraced between a pair of gaskets 61. Threadedly secured to the upper end of the body is a cap 62 having its upper end formed with a transverse flange 63 for embracing 55 the gaskets and marginal edge of the cover element 60, forming a seal against the passage of fluid around the marginal edge of the cover.

It will be apparent that the bulb portion 54 of the thermometer by reason of its close association to the metal of the body 50 which in turn is in direct contact with the impeller member 11^c, will respond rather quickly to the temperature changes in the body 11. To insure against an insulating body of air surrounding 60 the bulb 54, the apertures 52 permit circulation of the air contained in the recess 51. These openings may also permit a small quantity of the splash of the fluid to come in direct contact with the bulb of the thermometer while the impeller member is in operation, thereby assisting in accurately indicating the temperature of the washing fluid.

Although I have herein shown and described certain preferred embodiments of my invention, 75 manifestly it is capable of further modification

and rearrangement without departing from the spirit and scope thereof. I do not, therefore, wish to be understood as limiting this invention to the precise forms herein disclosed, except as it may be so limited in the appended claims. 5

I claim:

1. The combination with a washing machine having a tub adapted to contain washing fluid and clothes to be washed; of an impeller member mounted in the tub and rotatable about a vertical axis and including an upper portion normally extending above the normally stationary level of the washing fluid, said impeller being formed of metal of high heat conductivity, a head secured to said upper portion of the impeller member, and means within said head for visually indicating the approximate temperature ranges of the washing fluid. 10

2. The combination with a washing machine having a tub adapted to contain washing fluid and clothes to be washed; of an impeller member mounted in the tub and rotatable about a vertical axis and including an upper portion normally extending above the normally stationary level of the washing fluid, said impeller being formed of metal of high heat conductivity, and a head secured to said upper portion of the impeller member, comprising a body, a graduated dial on the upper end of the body, temperature responsive means carried by the body and having indicating means above the dial, a transparent cover at the upper end of the body above said indicating means, gaskets at the marginal edges of opposite faces of the cover, and a cap secured to the body and having an inturned flange engaging the upper gasket for compressing the gaskets and sealing the marginal edge of the cover. 20

3. The combination with a washing machine having a tub adapted to contain washing fluid and clothes to be washed; of an impeller member mounted in the tub and rotatable about a vertical axis and including an upper portion normally extending above the normally stationary level of the washing fluid, said impeller being formed of metal of high heat conductivity, and a head secured to said upper portion of the impeller member, comprising a body having an upwardly open recess, a bimetallic element mounted in said recess, a graduated dial on the upper end of body, an indicator connected to the bimetallic element 30 and extending over the dial, a transparent cover mounted on the body over said indicator, and a closure cap connected to the body and having an inturned flange at its upper end for sealing the marginal edge of the cover. 35

4. The combination with a washing machine having a tub adapted to contain washing fluid and clothes to be washed; of a movable impeller member in the tube, and a head mounted upon the upper portion of the impeller member, including temperature indicating means directly connected to the impeller member for indicating the approximate temperature ranges of the washing fluid, said means, comprising a body having a pair of upstanding transversely spaced apart ears, a spirally coiled bimetallic strip, a pin secured to the inner end of the coil and having its ends secured to said ears, the outer lateral surface of the outer convolution of the coil having a graduated area to indicate temperature ranges, and a closure cap connected to the body and enclosing the coil, said cap having a transparent window with which the graduated surface of the coil registers. 60

5. The combination with a washing machine 70

- having a tub adapted to contain washing fluid and clothes to be washed; of an impeller member mounted in the tub and rotatable about a vertical axis and including an upper portion normally 5 extending above the level of the washing fluid, and a head mounted upon the upper portion of the impeller member comprising a temperature indicating device including a body connected to said portion of the impeller member and having 10 its upper end provided with a pair of transversely spaced apart upstanding ears, a spirally coiled bimetallic strip, a pin secured to the inner end of the coil and having its ends secured to said ears, the outer lateral surface of the outer 15 convolution of the coil having a graduated area to indicate temperature ranges, and a closure cap connected to the body and enclosing the coil, said cap having a transparent window with which the graduated surface of the coil registers.
- 20 6. The combination with a washing machine having a tub adapted to contain washing fluid and clothes to be washed; of an impeller member mounted in the tub and rotatable about a vertical axis and including a portion extending above the 25 normal level of the washing fluid, and a head mounted upon the upper portion of the impeller member comprising a temperature indicating device including a body connected to said upper portion of the impeller member and having an 30 upwardly open recess, a graduated dial on the upper end of said body, a fluid thermal responsive tube having a bulb portion extending into the recess and an arcuately formed portion disposed over said dial, a transparent cover on the upper 35 end of the body above said dial and arcuately formed portion of tube, and a closure cap connected to the body and formed for sealing the marginal edge of said cover.
7. The combination with a washing machine 40 having a tub adapted to contain washing fluid and clothes to be washed; of an impeller member mounted in the tub and rotatable about a vertical axis and including a portion extending above the normal level of the washing fluid, and a head 45 mounted upon the upper portion of the impeller member comprising a temperature indicating de-

vice including a body connected to said upper portion of the impeller member and having an upwardly open recess, a graduated dial on the upper end of said body, a fluid thermal responsive tube having a bulb portion extending into the recess and an arcuately formed portion disposed over said dial, said arcuate portion of the tube and dial being disposed at an angle oblique to the axis of the impeller, a transparent cover on the upper end of the body above said dial and arcuately formed portion of tube, and a closure cap connected to the body and formed for sealing the marginal edge of said cover. 5

8. The combination with a washing machine 15 having a tub adapted to contain washing fluid and clothes to be washed; of an impeller member mounted in the tub and rotatable about a vertical axis and including a portion extending above the normal level of the washing fluid, and a head mounted upon the upper portion of the 20 impeller member comprising a temperature indicating device including a body connected to said upper portion of the impeller member and having an upwardly open recess, a graduated dial on the upper end of said body, a fluid thermal responsive tube having a bulb portion extending into the recess and an arcuately formed portion disposed over said dial, said body having one or 25 more openings from the exterior thereof to said recess, a transparent cover on the upper end of the body above said dial and arcuately formed portion of tube, and a closure cap connected to the body and formed for sealing the marginal edge of said cover. 30

9. The combination with a washing machine 35 having a tub adapted to contain washing fluid and clothes to be washed; a movable impeller member in the tub, a head having a chamber therein mounted upon the upper end of the impeller member, and a temperature indicating 40 means enclosed in said chamber for indicating the approximate temperature ranges of the washing fluid, said head including a transparent portion through which indications of the indicating means are readable. 45

DAVID A. LUNDY.
